The ornamental design for a handle for cutting tool, as shown and described.

DESCRIPTION

FIG. 1 is a perspective view of a handle for cutting tool showing my new design;

FIG. 2 is a front view thereof, the rear view being symmetrical to the front view;

FIG. 3 is a left view thereof;

FIG. 4 is a right view thereof;

FIG. 5 is a top view thereof; and,

FIG. 6 is a bottom view thereof.

The broken lines depicted as dot-dash-dot should be interpreted as boundaries, and the broken lines depicted as dash-dash-dot depict portions of the handle for cutting tool in which the design is embodied that are not considered part of the claimed design.
